(57) **ABSTRACT**

A new and distinct variety of nectarine tree, *Prunus persica* var. *nucipersica*, cv. 'Sunect29', is characterized by early ripening, circular fruit with a sweet to mid-acid flavor. The fruit of 'Sunect29' is very large-sized and has very firm flesh that is semi-adherent to the stone.

1 Drawing Sheet

1

Latin name of the genus and species claimed: *Prunus persica* var. *nucipersica*.
Variety denomination: 'SUNECT29'.

BACKGROUND AND SUMMARY OF THE INVENTION

This application relates to the discovery and asexual propagation of a new and distinct variety of nectarine, *Prunus persica* var. *nucipersica* cv. 'Sunect29'. The new variety was first originated by hybridization and identified in May 2019 by Terry A. Bacon and Terrence J. Frett as breeder number 'NE2384'. The new variety was first evaluated by Terry A. Bacon and Terrence J. Frett near Wasco, Calif. in Kern County.

A new and distinct variety of nectarine tree, *Prunus persica* var. *nucipersica*, cv. 'Sunect29', is characterized by early ripening, circular fruit with a sweet to mid-acid flavor. The fruit is very large-sized, with very firm flesh that is semi-adherent to the stone.

The pollen parent is 'Supechtwentytwo' (U.S. Plant Pat. No. 30,979), and the seed parent is 'PE1042' (unpatented breeding selection). The parent varieties were first crossed in February 2016, the date of first sowing being February 2017 and the date of first flowering being February 2019. The new nectarine variety 'Sunect29' was first asexually propagated by Terry A. Bacon and Terrence J. Frett near Wasco, Kern County, Calif. in February 2020 by dormant grafting.

The new variety 'Sunect29' is distinguished from its seed parent, 'PE1048' in that the fruit of the new variety ripens about 19 days later than the fruit of the seed parent. The fruit of the new variety 'Sunect29' also has a higher brix at 15% compared to 12% for 'PE1048'.

The new variety 'Sunect29' is distinguished from its pollen parent, 'Supechtwentytwo' in that the fruit of the new variety ripens about 12 days later than that of the pollen parent. The new variety 'Sunect29' also has a larger fruit

2

weight of 195 g compared to 180 g for 'Supechtwentytwo'. The new variety 'Sunect29' also does not have pubescence like 'Supechtwentytwo'.

The new variety 'Sunect29' resembles 'Zee Fire' (U.S. Plant Pat. No. 13,501) in that the fruit of both varieties have yellow flesh and ripen at about the same time. The new variety 'Sunect29' differs from 'Zee Fire' in that the fruit weight of the new variety is about 195 g compared to about 146 g for 'Zee Fire'. The new variety 'Sunect29' also differs from 'Zee Fire' in that the fruit of the new variety has a brix of 15% and a Brix:Acid ratio of 20, compared to a brix of 13% and a Brix:Acid ratio of 10 for 'Zee Fire'.

The new variety 'Sunect29' resembles 'Sunecttwentyone' (U.S. Plant Pat. No. 18,114) in that the fruit of both varieties have yellow flesh. The new variety 'Sunect29' differs from 'Sunecttwentyone' in that the fruit weight of the new variety is about 195 g compared to about 180 g for 'Sunecttwentyone'. The new variety 'Sunect29' also differs from 'Sunecttwentyone' in that the ripening of the fruit of the new variety starts about 7 days later than 'Sunecttwentyone'.

The new variety 'Sunect29' has been shown to maintain its distinguishing characteristics through successive asexual propagations by, for example, cuttings and grafting.

BRIEF DESCRIPTION OF THE PHOTOGRAPH

The accompanying color photographic illustration, FIG. 1, shows typical specimens of the foliage and fruit of the new nectarine variety 'Sunect29'. The illustration shows the upper and lower surface of the leaves, an exterior and sectional view of a fruit divided across its suture plane to show flesh color, pit cavity and the stone. The photographic illustration was taken shortly after the fruit was picked and the colors are as nearly true as is reasonably possible in a color representation of this type.

35 DETAILED DESCRIPTION OF THE PREFERRED EMBODIMENT

Throughout this specification, color names beginning with a small letter signify that the name of that color, as used

in common speech is aptly descriptive. Color names beginning with a capital letter designate values based upon The R.H.S. Colour Chart published by The Royal Horticultural Society, London, England, 1986.

The descriptive matter which follows pertains to 2-year-old 'Sunect29' plants grown in Wasco, Kern County, Calif., and is believed to apply to plants of the variety grown under similar conditions of soil and climate elsewhere. Observations were made in 2021.

TREE

General: (Measurements were taken on 2-year-old trees unless otherwise noted.).

Size.—Large. Normal for most nectarine varieties.

Spread.—Normal for most nectarine varieties. Reaches a spread of 5 m with normal vase pruning.

Vigor.—Strong. Approximately 1.8 to 2 meters of growth in the first growing season.

Growth.—Semi-upright.

Productivity.—Very productive. About 700 25-pound cartons per acre on mature trees.

Bearer.—On one-year old shoots.

Fertility.—Self-compatible.

Hardiness.—Hardy in all fruit growing areas of California.

Disease resistance/susceptibility.—No specific testing for relative plant disease resistance/susceptibility has been undertaken. Under close observation in Kern County, Calif., no particular plant/fruit disease resistance/susceptibility has been observed.

Chilling requirements.—About 150 hours at or below 7.2° C.

Shipping and storage characteristics.—Excellent for about 5 weeks.

Trunk: (Measurements were taken at approximately 30 cm above the soil line.).

Diameter.—Approximately 16 cm.

Texture.—Medium shaggy, increasing with age.

Trunk color.—About medium Greyed-Orange 173A becoming darker with age.

Branches: (Measurements were taken at approximately 90 cm above the soil line.).

Size.—Approximately 12 cm.

Texture.—Smooth on young wood, increasing roughness with tree age.

Color.—About medium Greyed-Orange 173A becoming darker with age.

Lenticels.—Present.

Lenticels numbers.—Plentiful.

Lenticels density.—Approximately 12 per cm².

Lenticels color.—About Light Grey 201D.

Lenticels length.—Approximately 3 mm.

Lenticels width.—Approximately 1 mm.

One year old shoots: (Data taken in September at the midpoint of current-season growth.).

Size.—Average diameter approximately 5 mm.

Color.—Topside: About Medium Greyed-Orange 164B. Underside: About Medium Greyed-Orange 164B.

Internode length.—About 2.0 cm, midway on shoot.

Lenticels diameter.—About 0.3 mm.

Lenticels.—Plentiful.

Lenticels color.—About White 155D.

Intensity of anthocyanin on upper side of shoots.—Absent or very sparse.

Vegetative buds: (Data were taken in September at the midpoint of current-season growth.).

Position of vegetative bud in relation to shoot.—Slightly held out.

Size.—Medium, approximately 1.5 mm×2.5 mm.

Shape.—Ovoid.

Shape of apex.—Obtuse.

Color.—About Dark Brown 200B.

Flower buds: (Data were taken in September at the midpoint of current-season growth.).

Distribution.—2 flowers buds per node, on one-year old shoots.

Shape.—Rounded.

Dimensions.—Approximately 4 mm×2.5 mm.

Color.—About Dark Greyed-Orange 165A.

Ratio of flower buds to vegetative buds.—2 flowers buds: 1 vegetative bud.

FOLIAGE

Leaves: (Data taken on fully expanded leaves).

Size.—Medium.

Average length.—Long; approximately 13.0 cm without petiole.

Average width.—Medium; approximately 5.0 cm.

Ratio of length to width.—Very elongated, approximately 2.6:1.

Shape.—Lanceolate.

Color of upper side.—About Dark Green 139A.

Color of lower side.—About Medium Green 139B.

Glossiness of upper side.—Medium.

Angle at apex (excluding tip).—Acute.

Shape of base.—Cuneate.

Venation.—Pinately net veined.

Vein color.—About Light Green 139D.

Surface texture.—Smooth.

Shape in cross-section.—Concave.

Profile.—Up-folded.

Leaf blade tip.—Curved downward.

Undulation of margin.—Pronounced.

Density of pubescence of lower side.—Absent or very sparse.

Incisions of margin.—Crenate.

5 Petiole:

Length.—Medium; approximately 10 mm.

Diameter.—Approximately 3 mm.

Color.—About Light Green 139D.

50 Stipules:

Number/leaf bud.—Approximately 2 when present.

Typical length.—Medium, approximately 8 mm.

Color.—About Dark Greyed-Red 180A when dried.

Persistence.—Falls off.

Leaf glands:

Form.—Globose.

Average number and arrangement.—0-5, usually 4, arranged alternately on petiole and base of leaf.

Diameter.—Approximately 2 mm.

Color.—About Medium Greyed-Orange 164C.

FLOWERS

General:

Time of beginning of flowering.—Very early for the San Joaquin Valley, Calif.

Flower blooming period.—First bloom: Approximately February 4 in Wasco, Calif. Location of First bloom:

Toward base of the tree. Full bloom: Approximately February 8 in Wasco, Calif. Location of Full bloom: Central part of the tree canopy.

Duration of bloom.—Approximately 10 days.

Flower diameter.—Medium, approximately 27 mm.

Flower form.—Non-showy.

Pedicel:

Length.—Long, approximately 10 mm.

Diameter.—Approximately 1 mm.

Color.—About Dark Greyed-Red 180A when dry.

Pubescence.—Absent.

Sepals:

Number.—5.

Length.—Approximately 6 mm.

Diameter.—Approximately 4 mm.

Shape.—Triangular.

Color.—About Medium Red 44A.

Texture.—Smooth to slightly bumpy.

Margins.—Smooth.

Position.—Adpressed to petals.

Frequency of flowers with double sepals.—None.

Receptical:

Depth.—Medium, approximately 2 mm.

Pubescence of inner surface.—Absent.

Pubescence of outer surface.—Absent.

Petals:

Number.—5.

Arrangement.—Slightly overlapping.

Color.—About Light Red 54D.

Surface texture.—Smooth.

Length.—Long, approximately 13 mm.

Width.—Approximately 7 mm.

Shape.—Elliptic.

Apex shape.—Rounded.

Base shape.—Narrows at point of attachment.

Undulation of margin.—Medium.

Frequency of flowers with double petals.—Never.

Pistil:

Length.—Approximately 37 mm.

Ovary diameter.—Approximately 1.5 mm.

Pubescence.—Absent.

Stigma extension in comparison to anthers.—Above.

Frequency of supplementary pistils.—Few.

Stamens:

Number.—Approximately 32-38. Average 34.

Length.—Variable, ranging approximately from 3 mm to 10 mm.

Filament color.—About White 155A.

Pollen color.—About Medium Red 52A.

Position.—Perigynous.

FRUIT

General: (Description taken near Wasco, Kern County, Calif.).

Time of beginning of fruit ripening.—Early for the San Joaquin Valley, Calif.

Harvest.—

Date of first pick.—Approximately May 15.

Date of last pick.—Approximately May 25.

Maturity when described: Firm-mature.

Peduncle:

Length of stem.—Short, approximately 7 mm.

Diameter of stem.—Approximately 7 mm.

Color of stem.—About Medium Greyed-Orange 164B.

Size:

Average size.—Very large.

Diameter in line with suture plane.—Approximately 77 mm.

Diameter perpendicular to suture.—Broad, approximately 80 mm.

Average weight.—Approximately 195 gm.

Height.—Tall, approximately 82 mm.

5 Shape:

Viewed from apex.—Circular.

In lateral view, perpendicular to suture.—Circular.

In-line with suture.—Circular.

Symmetry.—Symmetric or slightly asymmetric.

Shape of base.—Slightly depressed.

Shape of apex.—Rounded.

Depth of stalk cavity.—Medium, approximately 10 mm.

Width of stalk cavity.—Medium, approximately 20 mm.

Depth of suture.—Absent or very shallow.

Skin:

Thickness.—Medium, typical of most varieties.

Adherence to flesh.—Strong.

Surface texture.—Nearly smooth.

Taste.—Neutral.

Reticulation.—Absent.

Tendency to crack.—Rare.

Pubescence.—Absent.

Bloom on skin.—Absent or very weak.

Ground color.—About Medium Yellow 13B.

Relative area of over color of skin.—Nearly whole surface.

Overcolor.—About Dark Red, ranging from Dark Red 53C to Dark Red 53A.

Pattern of over color of skin.—Solid.

Number of lenticels.—None to a few.

Size of lenticels.—Very small approximately 0.5 mm.

Flesh:

Ripens.—Evenly.

Texture.—Slow-softening, melting, firm-juicy.

Color.—About Medium Yellow 13C.

Flavor.—Sweet, mid-acid.

Firmness.—Very firm.

Juiciness.—Medium, able to squeeze free juice easily.

Acidity.—Medium for nectarines, 0.80% titratable acidity.

Sweetness.—Medium.

Brix.—Approximately 15% at harvest.

Adherence of stone to flesh.—Semi-adherent.

Fiber.—Medium.

Stone:

Stone freeness.—Semi-free.

Stone size.—Size: Medium. Length: Approximately 30 mm. Diameter in line with suture: Approximately 24 mm. Diameter perpendicular to suture: Approximately 19 mm.

Color.—About Light Greyed-Orange 164C.

Position of maximum diameter.—Middle.

Stone shape.—Lateral view: Medium elliptic. Basal view: Broad elliptic. Ventral view: Broad elliptic.

Base shape.—Nearly straight.

Apex shape.—Pointed.

Ridges.—Rounded throughout.

Outgrowing keel.—Well developed.

Ventral edge.—Medium.

Dorsal edge.—Full, deep grooves.

Fibers.—Retains short fiber-like threads along ridges.

Symmetry in lateral view.—Symmetric.

Texture of lateral surface.—Rough.

Width of stalk-end.—Medium, approximately 4 mm.

Tendency to split.—Rare.

What is claimed is:

1. A new and distinct variety of nectarine tree as herein described and illustrated.

* * * * *
